Specification for Design.

Patented Oct. 25, 1921.

Application filed January 17, 1921. Serial No. 438,015. Term of patent 14 years.

To all whom it may concern:

Be it known that I, FRANK S. LAND, a citizen of the United States, residing at Kansas City, Jackson county, Missouri, have invented a new, original, and ornamental design for Pins, Watch-Fobs, Lapel-Buttons, Rings, Belt - Buckles, Seals, Pin - Buttons, Watchcases, or Articles of Similar Nature, of which the following is a specification, reference being had to the accompanying drawing, forming a part thereof.

In the drawing:

The figure shown represents a plan view of a pin embodying my new design.

I claim:

The ornamental design for a pin, watch fob, lapel button, ring, belt buckle, seal, pin button, watchcase, or article of similar nature, as shown.

FRANK S. LAND.
